Primary Examiner — Justin C Dodson*Assistant Examiner* — Olivia B. El-Nemri(74) *Attorney, Agent, or Firm* — Howson & Howson LLP(57) **CLAIM**

The ornamental design for a bottle, as shown and described.

DESCRIPTION

FIG. 1 is a top perspective view of a bottle according to my design;

FIG. 2 is a bottom perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines throughout the figures are for illustrative purposes and form no part of the claimed design, and the shade lines shown throughout are understood to represent contour only.

1 Claim, 7 Drawing Sheets(56)
